(57) **CLAIM**

The ornamental design for a dust collector tank, as shown and described.

DESCRIPTION

FIG. 1 is a perspective view of a dust collector tank of the present invention;

FIG. 2 is a back view of the dust collector tank of FIG. 1; FIG. 3 is a front view of the dust collector tank of FIG. 1; FIG. 4 is a left side view of the dust collector tank of FIG. 1;

FIG. 5 is a right side view of the dust collector tank of FIG. 1;

FIG. 6 is a top view of the dust collector tank of FIG. 1; and, FIG. 7 is a bottom view of the dust collector tank of FIG. 1. In the drawings, the portions of the dust collector tank shown in broken lines depict environmental subject matter and form no part of the claimed design.

1 Claim, 7 Drawing Sheets
